WILLIAM ROSE, OF GAINSBOROUGH, ENGLAND.

SHEET FEEDING AND GUMMING APPARATUS.

1,268,627.

Specification of Letters Patent. Patented June 4, 1918.

Application filed September 20, 1916. Serial No. 121,326.

To all whom it may concern:

Be it known that I, WILLIAM ROSE, a subject of the King of Great Britain, residing at Albion Works, Gainsborough, in the 5 county of Lincoln, England, have invented new and useful Improvements in Sheet Feeding and Gumming Apparatus, of which the following is a specification.

This invention has for its object to provide 10 improved apparatus for separating sheets of paper, or the like, from a pile of such sheets, applying adhesive matter to them, and feeding them to the required place, or machine such as a bag-making 15 machine.

The top sheet of the pile of sheets may be raised by any suitable mechanism such as for example, the mechanism described in the specification of British Letters Patent No. 20 6,815 A. D. 1915. When the rear edge of the top sheet has been raised a reciprocating slider, (which may be, for example, operated by a cam and levers from the main shaft of the machine) is caused to pass under the 25 said top sheet to completely separate it from the next sheet of the pile, should it have a tendency to adhere thereto throughout any part of its length. The said reciprocating slider is provided with a device such as a 30 gripper, or a projection, or grippers, or projections, or the like, to engage the separated top sheet and move it into position to be engaged by a gripper, or by grippers, or the like, on a segment, or segments, or the 35 equivalent, rotated by any suitable means. An adhesive applying-device, is, or adhesive-applying devices, are, provided to take up adhesive (which we will refer to as gum) from a roller, or rollers, rotatable in a gum 40 trough and apply the gum to the sheet as it is carried by the said segment, or segments. After the sheet has had the gum applied thereto it is carried farther by the aforesaid segment, or segments, beneath a 45 roller, or rollers, which deliver it onto a traveling conveyer, or the like, or in any other suitable way, to the bag-making machine, or other required place.

In order to prevent gum being applied to 50 the aforesaid segment, or segments, should

a sheet of paper not be in position thereon, there may be a groove in the segment, or in each segment, in such position that the gumming device will not come into contact with the bottom of the said groove when it 55 is not covered by a sheet. Or, with the same object part of the said segment, or of each segment, may be constituted by a portion of a movable bar so arranged that after a top sheet has been seized by the gripper, 60 or grippers, on the segment (or each segment) a finger, or the like, mounted on a spindle carried by the said segment (or each segment) is brought into engagement with the paper, or the like, the said finger, 65 or the like, being operated by a roller on an arm carrying the said finger and acting on a stationary cam. The said finger, or arm, also carries a rack engaging another rack fixed on a spindle mounted in the segment, 70 (or each segment). Also fixed to the said spindle is a toggle arm connected by a link (or by links) to the aforesaid bar which is loosely mounted on a spindle also carried by the segment. When a sheet is in position on the segment (or segments) the aforesaid finger, or the like, rests on the sheet and the bar is in its raised position so that it constitutes part of the segment and there 75 is consequently a continuous surface on 80 which the sheet is supported while the gum is applied to it. If a sheet has not been taken up by the segment (or segments) the finger, or the like, makes a further movement and the bar is turned to beneath the 85 plane of the surface of the segment and no gum is applied to the said segment.

The adhesive applying device may be of any suitable kind, such as a roller, or portion of a roller, or it may be a yieldable device adapted to evenly distribute the gum; 90 or other adhesive.

I will describe an arrangement according to my invention with reference to the accompanying drawings in which Figures 1 95 and 2 are an elevation and a plan respectively, Figs. 3 and 4 are an elevation and plan respectively of parts of the mechanism shown in Figs. 1 and 2 but drawn to a larger scale and showing more detail. 100

The mechanism for raising the sheets is not illustrated but, as aforesaid, it may be presumed to be like that described in the specification of British Letters Patent No. 5 6,815 A. D., 1915. When the rear edge of the top sheet has been raised a reciprocating slider 1, (operated from the main shaft 3, of the machine by a cam 2, which actuates, through an antifriction roller 2^a, a bell- 10 crank lever 3^a, connected by a link 3^b, to a sliding carriage 3^c, attached to the said slider 1) is passed under the said top sheet to completely separate it from the next sheet of the pile, should it have a tendency to add- 15 here thereto throughout any part of its length. The said reciprocating slider 1, is provided with grippers 4, and projections 5, to engage the separated top sheet and move it into position to be engaged by grippers 6, 6^a, on segments 7, 7^a, rotated by any suitable means. The adhesive-applying devices 8, 8^a, take up gum from rollers 9, 9^a, rotatable in a gum trough 10, and apply the gum to the sheet as it is carried by the said 20 segments 7, 7^a. After the sheet has had the gum applied thereto it is carried farther by the segments 7, 7^a, beneath rollers 11, (shown in Fig. 2 bearing upon a third segment 14) which deliver it onto a reciprocating conveyer 12, to the bag-making machine, or other required place.

In order to prevent gum from being applied to the segments should a sheet of paper not be in position thereon, there is a groove 35 13, in each segment, or in some of the segments, for example, as shown with respect to the segments 7 and 14, in such position that the gumming device appertaining to such segment will not come into contact 40 with the bottom of the said groove 13, when it is not covered by a sheet. In Figs. 3 and 4, the groove 13, in the segment 14, has a movable bar 15, therein which is so arranged that after a top sheet has been seized 45 by the top grippers 6, 6^a, a finger 16, mounted on a spindle 17, carried by the segment 7, is brought into engagement with the paper, or the like, the said finger 16, being operated by a roller 18, on an arm 19, formed in one with the said finger and acting on the stationary cam 20. The said finger 16, or arm 19, also carries a rack 21, engaging another rack 22, fixed on a spindle 23, mounted in the segment 7, (or each of 50 55 the segments). Also fixed to the said spindle 23, is a toggle-arm 24, connected by links 25, to an arm 26, pivoted, at 27, to the segment 14, and formed in one with the aforesaid bar 15. When a sheet is in position of the segments 7, 7^a, and 14, the finger 16, rests on the sheet and the bar 15, is in its raised position so that it constitutes part of the segment and there is consequently a continuous surface on which the sheet is

supported while the gum is applied to it. 65 If a sheet has not been taken up by either of the segments 7, 7^a and 14, the finger 16, makes a further movement and the bar 15, is turned beneath the plane of the surface of the segment 14, and no gum is applied to 70 the said bar.

The adhesive applying device may be of any suitable kind, such as a roller, or portion of a roller, as shown at 8, or a bar as shown at 8^a, or it may be a yieldable device adapted 75 to evenly distribute the gum; or other adhesive.

The device 8^a, for applying the gum to the segment 14, may be adapted to yield should an obstruction come between it and the said 80 segment so as to prevent the liability of damage, and this may be effected by providing the said device with an arm 28, (see Fig. 1) pivoted to a spindle 29, carried by an arm 29^a, rotatable on a shaft 30^a, the said 85 arm 28, being normally held against an abutment 30, by a spring 31. Any obstruction coming between the device 8^a, and the segment 14, would cause the arm 28, to turn on its pivot, against the action of the spring 90 30, and so damage will be prevented.

The gripper 6, is mounted on a spindle 32, carried by the segment 7, and it is caused to turn thereon, so as to open and close at the proper times, by a stationary cam 33, 95 with which an antifriction roller 35, on an arm 34, formed in one with the said gripper, engages as the segment rotates.

The grippers 4, 4^a, are mounted on the slider 1, so that they can turn and the tail 100 of each gripper is provided with an antifriction roller 36, which, as the slider reciprocates, engages with a stationary cam 37, of such form as to cause the gripper to open and close at the proper times. 105

What I claim is:-

1. In sheet feeding and gumming apparatus, the combination of a reciprocatable slider to pass under the top sheet of a pile of sheets, means on said slider for gripping the lifted sheet and holding it while it is shifted to position to be seized, independent means for gripping the thus shifted sheet, movable segments carrying the last named gripping means and over which segments 110 the sheet lies, means for applying adhesive to the sheet as it passes over the segments and means for delivering and conveying the gummed sheet to position for subsequent operation thereon.

2. In sheet feeding and gumming apparatus, a support for the sheet, said support being recessed at the point at which adhesive is to be applied to the sheet, means for applying adhesive to a portion of the sheet, a piece which normally forms a continuation of the supporting surface for the sheet, and a finger resting upon the sheet when the 125

latter is in position and serving to hold said piece in supporting position, together with means for moving said piece to position beneath said surface when no sheet is in position upon it to shift said piece out of the path of the adhesive applying device.

5 In testimony whereof I have signed my

name to this specification in the presence of two subscribing witnesses.

WILLIAM ROSE.
